UNITED STATES PATENT OFFICE.

FREDERICK M. GEISENDORFF, OF INDIANAPOLIS, INDIANA, ASSIGNOR OF ONE-HALF TO CHARLES W. ZIEGLER AND ONE-SIXTH TO CHARLES HAMBLEN, BOTH OF INDIANAPOLIS, INDIANA.

AMMONIA-PUMP MECHANISM FOR REFRIGERATION.

1,231,518.

Specification of Letters Patent. Patented June 26, 1917.

Application filed March 27, 1915. Serial No. 17,509.

To all whom it may concern:

Be it known that I, FREDERICK M. GEISENDORFF, a citizen of the United States, and a resident of Indianapolis, county of Marion, 5 and State of Indiana, have invented a certain new and useful Ammonia-Pump Mechanism for Refrigeration; and I do hereby declare that the following is a full, clear, and exact description thereof, reference being had to the accompanying drawings, in which like letters refer to like parts.

The object of this invention is the automatic prevention of the superheating of the valve in a refrigerating device or ammonia 15 pump or like situation. While the invention is primarily for such use, it involves a double valve which may be used in other combinations than that above suggested.

In an ammonia pump the valve controlling the inlet to the ammonia pump is highly chilled by the incoming ammonia, while the valve controlling the outlet from the pump becomes heated because of the passage of it by the ammonia while under high 25 pressure. Water jackets and other means have heretofore been employed for cooling the last-mentioned valve and it has often been difficult to protect it from the heat.

The object of this invention is to keep 30 said second valve cool without any additional means aside from the bare necessities of the valve construction.

The chief feature of the invention consists in associating the two valves together 35 so that they will control the temperature of each other. As herein shown, the valve controlling the outlet is located within the valve controlling the inlet of the ammonia. Hence, the outlet controlling valve will 40 always be kept at a reasonable temperature by the surrounding inlet controlling valve. There is also a corresponding reaction, to a lesser degree preferably, of the inlet valve and the outlet valve.

45 The full nature of the invention will be understood from the accompanying drawings and the following description and claims:

In the drawings, Figure 1 is a central 50 vertical section through the end of an ammonia pump cylinder and associated valve structure with the parts in idle position. Fig. 2 is a section on the line 2—2 of Fig. 1. Fig. 3 is a section on the line 3—3 of Fig. 1.

Fig. 4 is a similar section on a larger scale 55 through the pump cylinder and valve structure showing the parts in position during the intake. Fig. 5 is the upper part of what is shown in Fig. 4, with parts in their position during the compression movement 60 of the pump.

This device, as stated, was primarily devised for use in connection with refrigerators and pumping ammonia for refrigerator use.

65 There is a pump cylinder 10 with a piston 11 and upon the upper end of the cylinder there is a valve casing 12 secured. There is an inlet pipe 13 leading from some source of ammonia through a port 14 in said valve casing and there is a discharge pipe 15 leading from a discharge port 16 in said casing to the refrigerator. The casing 12 has an inwardly extending annular base ring or flange 17 at its lower end and a ring 18 at 70 about a middle point. A cylinder 20 is secured to the lower half of the case, being supported on the base ring 17 and surrounded and held in place by the intermediate ring 18. Said cylinder has a pair of 75 ports 21 on the opposite sides thereof in the form of vertical slots and communicating with a chamber 22 surrounding said cylinder 20.

80 Within the cylinder 20 there is an inlet or outer valve cylinder 24 vertically movable and having an annular flaring valve 25 on the lower end thereof and a pair of vertical slots or ports 26 on the opposite sides thereof. A spiral spring 27 surrounds 85 said valve cylinder and its lower end rests on an inwardly projecting annular shoulder 28 at the lower end of the cylinder 20 and the upper end of the spring bears against a ring 29 secured around the upper end of 90 the cylinder 24. This spring normally holds the valve 25 elevated and closed, as 95 shown in Fig. 1.

100 The outlet or inner valve casing 30 is cylindrical and its lower end projects into the outer valve cylinder 24 and is substantially flush with the lower end of said valve cylinder when it is in its upper or normal position. A laterally extending flange 31 from the upper end of the inner valve casing 105 is secured upon the cylinder 20 and it is held down by a cylinder 33 resting upon it and with a closed top extending to the top of

the main valve casing 12. There is a central extension 34 from the upper end of the inner valve casing 30 having a cross piece 35 which guides the valve stem 36 of the inner valve 37. This valve is beveled and seats in the tapering lower end of the inner valve case 30. A ring 38 is secured by radial arms to and around the valve stem 36 and moves upward with said valve stem. There are 10 ports 39 in the side walls of the extension 34 and openings 40 in the side walls of the cylinder 33 and a chamber 41 within the main outlet casing 12 and extending up to the outlet port 16. The lower end of the 15 inner valve case 30 is beveled on its outer edge and also the inwardly extending flange 28 from the cylinder 20 is beveled on its inner edge to furnish a suitable seat for the annular outer valve 25. A spiral spring 43 surrounds the valve stem 36 and bears at its upper end against the top 35 of the extension 34 and at its lower end on the ring 38. The purpose of this spring is to close the inner valve 37.

25 The operation is as follows:

On the downward movement of the pump piston 11 the outer valve is drawn down against the casing of its spring by the suction and ammonia enters from pipe 13 30 through ports 14, chamber 22 and ports 21 and 26 into the pump cylinder 10. The upper position of the parts is illustrated in Fig. 4. On the upward or return stroke of the pump piston, the outer valve 25 is elevated and seated by the pressure in the cylinder and the inner valve 37 is elevated and 35 opened against the influence of its spring and then the ammonia passes through the inner valve casing 30, ports 39, 40, 41 and 16 40 to the discharge pipe 15. Again on the down stroke of the pump piston the inner valve is thrown closed and the outer valve thrown open. Therefore, it is seen that the outer valve 37 and its casing are kept cool because 45 they are immediately surrounded by and located within the outer valve cylinder 24 which is cooled by the incoming ammonia. The incoming ammonia also while moving through the ports 26 comes in direct contact with the inner valve casing and the 50 underside of the inner valve 37 and cools it.

While the invention has been made and

described particularly for use in pumping ammonia, still it is applicable for pumping anything else, as substantially the same considerations of temperature of the valves will arise, the outer valve being kept cool by the inner valve. And so far as this invention is concerned the particular construction of valves herein may be altered without changing the invention, so long as the valves are in such relation to each other that the outer valve structure will be kept cool by the inner valve structure.

The invention claimed is:

1. The combination with a pump, of a cylindrical valve structure for controlling the inlet to the pump, and a valve structure controlling the outlet therefrom which is located within the valve structure for controlling the inlet so as to be kept cool by the inlet controlling valve structure.

2. The combination with a pump, of a valve casing secured thereon having an inlet port and an outlet port, a valve structure in 75 said valve casing for controlling the inlet to said pump from said inlet port, and a valve structure within said casing for controlling the outlet from the pump to said outlet port, one of said valve structures being located 80 within the other.

3. The combination with a pump, of an outer valve casing secured thereto having near its lower end an outlet port, a vertically movable outer valve cylinder within 85 said casing having an annular valve on its lower end, ports therethrough communicating with the inlet port, a spring tending to hold said outer valve cylinder and valve elevated and closed, an inner valve casing stationary and extending down into said outer valve cylinder with its lower end open and having an outlet port through its upper end, an inner valve within said inner valve casing, and a spring within said inner valve 90 casing tending to hold said inner valve closed.

In witness whereof, I have hereunto affixed my signature in the presence of the witnesses herein named.

FREDERICK M. GEISENDORFF.
